UNITED STATES PATENT OFFICE.

WILLIAM J. MACKLE, OF ST. LOUIS, MISSOURI.

MOTOR.

Application filed April 17, 1919, Serial No. 290,500.

To all whom it may concern:

Be it known that I, WILLIAM J. MACKLE, a citizen of the United States, residing at St. Louis, Missouri, have invented a certain new and useful Improvement in Motors, of which the following is a full, clear, and exact description, such as will enable others skilled in the art to which it appertains to make and use the same, reference being had 10 to the accompanying drawings, forming part of this specification, in which—

Figure 1 is a longitudinal sectional view through my improved motor.

Figure 2 is a cross-sectional view on line 15 2—2 of Figure 1 looking in the direction of the arrow.

Figure 3 is a cross-sectional view on line 3—3 of Figure 1.

Figure 4 is a detail view of several of the 20 parts associated with the rocking valve.

Figure 5 is a sectional view through a portion of the cam plate operated by the piston for rocking the valve.

Figure 6 is a fragmentary side elevational 25 view of the piston.

Figure 7 is a sectional view of one of the valve rocking plates with which the piston co-operates.

Figure 8 is an enlarged sectional view 30 through the valve mechanism.

This invention relates to a new and useful improvement in motors for drills, but is adapted for use in connection with automobiles and stationary power plants. The objects of the present invention are to simplify 35 the construction and cheapen the cost of production per rated horse-power and to enable the device to be easily assembled and readily repaired.

40 In the drawings, I have shown my improved motor as adapted to use as a drill in which air or steam may be used as the motive power, and it is obvious that with slight modifications the motor can be adapted for 45 use in driving automobiles or as a stationary engine.

1 indicates a flanged cylinder, preferably in the form of a casting having a valve chamber 2 located to one side thereof and 50 which communicates with the bore of cylinder 1 by means of suitable openings 3 constituting ports in which operate parts of the valve-operating mechanism. 4 is the front cylinder head having a threaded boss to 55 which are secured packing nuts for packing the rotatable hollow shaft 6 and providing

a bearing for the front end thereof. This casting 4 extends up to include the valve casing and is provided with an opening in which is arranged a hollow valve cap 7 through the opening in which passes the exhaust from the front end of the cylinder. 8 is a rear cylinder head having a similar extension for receiving a hollow valve cap 9 through the opening in which exhaust passes 65 from the rear end of the cylinder.

10 is a hollow piston rod mounted upon the shaft 6, which shaft 6 may be designated as the driving shaft, the sleeve or hollow piston rod 10 being designed to slide longitudinally upon the driving shaft 6 while the latter rotates. 11 is a piston head secured in a suitable mounting, preferably by a threaded connection, to the forward end of the hollow piston rod 10, said piston head 75 having the usual packing rings 12. The piston comprising the head and hollow rod 10 are intended to reciprocate within cylinder 1 and passing through the packing nut mounted on the rear cylinder head 8, the 80 piston rod 10 extends into a chamber formed by a cylinder 13 secured to the rear cylinder head 8. This cylinder 13 is closed at its rear end by means of a head 14 and is exteriorly threaded to accommodate a capped 85 sleeve 15 having handles 16 by which the drill may be fed, as when boring through metal and the point at the rear end of the cap piece is placed under what is known as a "lazy man."

I do not deem it necessary in the present application to disclose the operation of this feeding mechanism as the same is disclosed in Patent No. 1,369,256 granted to me February 22, 1921.

90 Chamber 2 is connected in any suitable manner to a source of air or steam supply and located within said chamber is a rocking valve, parts of which are best shown in Figure 4. 28 indicates an open ended 100 cylinder in the ends of which are arranged the heads of the valve stems 29, the heads of said valve stems having longitudinally elongated openings to permit a slight independent longitudinal movement of each of said stems relative to their supporting connecting member 28. The cylinder 28 is provided with openings registering with the elongated openings in the heads of the valve stems and through these openings are passed pins 110 30, see Figure 3, which pins extend up into chambers arranged above the valve casing

and having seats or saddles formed in their upper ends for receiving the locking member of a spring follower 31 co-operating with a spring 32 bearing against a semispherical rocker 33 seated in a cap piece 34 arranged in an extension of the valve chamber, as shown in Figure 3. The purpose of this construction is to cause the cylinder 28, when it is rocked past a position of dead center, to be carried the remainder of its rocking movement under the impelling action of springs 32, of which there are two, as shown in Figure 1, arranged at each end of cylinder 28 so that their combined action on cylinder 28 will be exerted with the least possible torsional strain on the cylinder which is thus substantially balanced. The cap pieces 34 are formed with recesses in which the upper ends of rods connected to the spring seats 31 and which slide through the semispherical heads 33, may operate as the cylinder is rocked from one position to another. The arc of movement is slight but in the position of dead center the rods project slightly above the semispherical spring seats 33 and the space in the cap pieces 34 is provided to accommodate this projection of the rod through the spring seats 33. The bore of the valve chamber 2 is slightly enlarged at each end to receive and seat valve seats 35 against the inner faces of which operate the intake valves 36. These intake valves are provided with projections 36^a, see Figures 4 and 8, which operate in notches 28^a in cylinder 28 there being sufficient space in said notches to permit of lost motion so that the valves 36 are only operated a short distance near the end of the movement of cylinder 28. The cylinder 28 is spaced apart from the valve casing by means of lugs 1^b and the heads on the ends of the valve stems 29 bear against the lugs 36^a, there being a spring 37 located between said heads so as to force a chamfered shoulder on the valve stem against the valve seats 35 tending to press them outwardly or away from each other. This outward pressure is resisted by a sleeve 38 which is located between the valve seats 35 (for the intake valves) and the valve seats 39 (for the exhaust). These valve seats 39 are held in position by the piston heads 4 and 8, respectively, together with their valve caps 7 and 9. The valve seats 39 are provided with blind bearings in which the outer ends of the valve stems 29 are seated, the valve stems providing a mount for the exhaust valves 40 which bear against the seats 39. These valves 40 are provided with lugs 40^a between which are located rock arms 41, (see Figures 2 and 4), the lower ends of said rock arms being bifurcated or forked for purposes to be hereinafter described. The upper side of valve 40 is provided with a lug or projection 40^b operating in a groove in the

sleeve 38 to limit or determine the oscillating movement of valve 40 so as to insure proper registration of its openings with the openings in the valve seat 39 and also the proper closure thereof. A pin 42 serving as a spline, (see Figure 1) holds the valve seats 39 in proper position.

45 indicates rocker plates arranged at each end of the cylinder 1, (see Figures 1 and 2) which rocker plates are provided with projections 45^a which enter the space between the prongs of the valve rocking arms 41, said arms being pinned or otherwise fastened to the valve stems, as shown. Each rocker plate is also provided with a cam face 45^b forming one wall of an opening or recess therein with which cam face co-operates a cam projection 11^a on the piston head. There are four cam faces on the rocker plates with which the four cam projections 11^a co-operate. The operation of the valve mechanism is as follows:

As the piston reciprocates rearwardly one of the cam faces 11^a carried thereby will engage a cam face 45^b on the rocker plate, and as the piston is held against rotary movement by the cross-head 19, the rocker plate 45 will be operated so that the finger 45^a thereof engaging one of the bifurcated rocker arms 41 on a valve stem will cause said valve stem to be rocked and with it the sleeve 28. When one of the rocker arms 41 is operated by finger 45^a of a corresponding rocker plate 45, a corresponding exhaust valve 40 and a corresponding valve 100 stem 29 are operated. The enlarged ends of valve stems 29 being seated within each end of sleeve 28 and operatively connected thereto by pins 30, sleeve 28 will be rocked at every operation of either one of said 105 rocker arms to actuate intake valves 36 simultaneously with the positioning of exhaust valves 40.

Thus, when one of the rocker arms 41 is operated to exhaust cylinder 1, the corresponding exhaust valve 40 is positioned so as to have its ports in register with the ports on the stationary seat 39, whereby the fluid can pass from that end of the cylinder through the aligned ports of exhaust valve 115 40 and seat 39 and then through the opening in head 7 or 9 into the atmosphere.

Upon the operation of sleeve 28, inlet valves 36, by virtue of the fact that lugs 36^a projecting from said valves occupy notches 120 28^a formed in the ends of said sleeve, will be operated simultaneously so as to position one of said inlet valves so that the ports formed therein are in register with ports formed in the corresponding stationary valve seat 35 and the steam or air can pass from chamber 2 to one end of cylinder 1. The other of said inlet valves is operated to move out of cooperative relation with its stationary seat 35 so that the open- 130

ings formed in said inlet valve 36 and its respective seat 35 are out of alignment with each other and the fluid cannot enter this end of cylinder 1.

- 5 Simultaneously with the operation of intake valves 36, exhaust valves 40 are actuated so that each one of said exhaust valves cooperates with its corresponding intake valve, whereby when one of the intake valves 10 36 is opened, the corresponding exhaust valve 40 is closed, and vice versa. Exhaust valves 40 are loosely mounted on valve stems 29 and are operated by rocker arms 41 by means of lugs 40^a which project outwardly 15 from said valves and are disposed to each side of arms 41 and lie in the path of movement thereof. Lugs 40^a are spaced from each other a sufficient distance so that arm 41 has a predetermined amount of lost motion with respect to valves 40, whereby said 20 valves are actuated during the final movement of said arms and receive snap action under the influence of springs 32. When the springs 32 are compressed and move 25 past a position of dead-center, the energy stored therein will cause the sleeve 28 to be rocked the remainder of its intended distance, which is determined by the lugs or 30 projections on the intake and exhaust valves, respectively. In the operation under consideration, the rearward movement of the piston will cause the exhaust valve at the rear end of the cylinder to be closed, i. e., its ports, and thrown out of register with its 35 valve seat and inlet or intake valve 35 at the rear end of the cylinder to be moved to a position where its ports will be thrown into register with its valve seat 36. The compressed air or steam which is admitted to 40 the space around the cylinder 28 will pass through the notches 28^a and thus be enabled to pass through the registering openings of the intake valve at the rear end of the cylinder, then by virtue of the pressure thus admitted at this point the piston will be caused 45 to move forward. Coincidently with the reversal of the valves at the end of the cylinder occasioned by the piston reaching the limit of its rearward stroke, the valves 50 at the forward end of the cylinder will likewise be reversed because of the connection of the cylinder 28 therewith; so that the intake valve will be closed and the exhaust valve opened when the piston starts on its forward 55 movement. Upon reaching the forward limit of its movement, the piston will engage the rocker plate 45 mounted on the forward cylinder head to close the exhaust valve at the forward end of the cylinder and open 60 the intake valve at that end and, through the means above described, open the exhaust valve at the rear end of the cylinder and close the intake valve at the rear end.

The purpose of providing lost motion in 65 the throw of the valves is to reduce the arc

of their movement from an open to a closed position and at the same time give a greater arc of movement to enable the springs 32 to act in snapping the valve cylinder 28 from one position to another so that said 70 springs may be operated efficiently.

By the employment of my translating device for converting reciprocating motion into a rotary movement, it will be observed that dead centers are impossible, it making 75 no difference where the piston stops—the admission of pressure will cause the piston to move and start the shaft to rotating.

By providing a plurality of ports in the valves and arranging a lost motion between 80 the valve operating the cylinder and the valves, the valves are moved a relatively short distance while the cylinder 28 operates through a greater arc of a circle, thus enabling the springs to store up energy in 85 passing over a dead-center position thereby effecting a quick snap action in opening and closing the valves. Furthermore, the valves being seated on the pressure side of the valve seats will be held by the pressure to 90 their seats and be constantly ground in position so that they will have a tight fit at all times.

I do not in this application claim the means for converting the reciprocating motion of the piston into a rotary motion, as 95 the same is shown and described in a companion application filed by me November 14, 1919, Serial No. 338,068.

What I claim is:

1. A motor comprising a cylinder, a reciprocating piston in said cylinder, a valve chamber extending from one end of the cylinder to the other and communicating with said cylinder and having intake and exhaust 100 ports, means arranged within said cylinder and operable by said piston, oscillating valves in said chamber arranged at each end of said cylinder for controlling said ports and initially actuated by said means and 105 springs for holding said valves in their home positions.

2. A motor comprising a cylinder, a reciprocating piston therein, a valve chamber communicating with said cylinder and the 110 atmosphere, valve seats in said chamber, oscillating valves co-operating with said valve seats, means for oscillating said valves, a sleeve arranged in said valve chamber, connection including the sleeve for operatively 115 interengaging said valves, and yielding means for imparting a snap oscillatory movement to said sleeve after the valves have been initially moved by their main operating means.

3. A motor comprising a cylinder, a reciprocating piston, rocker plates mounted in said cylinder and actuated by the reciprocating piston, a valve chamber communicating with said cylinder, valve stems with- 120 125 130

4

in said valve chamber, rocker arms fixed to said stems and in engagement with the rocker plates, and valves adapted to be actuated by said valve stems.

5. A motor comprising a cylinder and a piston in combination with a valve casing having a valve chamber, valve seats fixed in said chamber, a tubular member supported in said chamber, valve stems carried by 10 said tubular member, valves operatively mounted on said stems and co-operating with said valve seats, rocker arms fixed to said valve stems and in engagement with the rocking mechanism of said motor and rocking mechanism operated by the motor for imparting rocking motion to said valves.

6. A motor comprising a cylinder, a reciprocating piston therein, cam projections on said piston, rocker plates arranged at 20 the ends of said cylinder, cam faces on said plates and cooperating with the cam projections on the piston, whereby said rocking plates are caused to partially rotate at each stroke of the piston, and valve mechanism 25 actuated by said rocker plate.

7. A motor comprising a cylinder, a reciprocating piston therein, a valve casing communicating with said cylinder and having intake and exhaust ports, oscillating intake 30 valves in said valve casing and controlling the communication between the intake port and said cylinder, oscillating exhaust valves in said valve casing and controlling communication between the exhaust ports and said 35 cylinder, and means located wholly within said cylinder and valve casing for oscillating said valves in synchronism with said reciprocating piston.

8. A motor comprising a cylinder, a reciprocating piston therein, rocker plates in 40 said cylinder and actuated by the piston, a valve casing having a valve chamber communicating with said cylinder and intake and exhaust ports, a tubular member arranged in said valve chamber, valve stems 45 arranged in the ends of said tubular member, valve seats fixed in said chamber, valves cooperating with said valve seats and adapted to be oscillated by the valve stems and 50 the tubular member, rocker arms carried by the valve stems and in engagement with said rocker plates for imparting motion to said valve stems and tubular member.

9. A motor comprising a cylinder, a reciprocating piston, rocker plates arranged at 55 each end of said cylinder and actuated by the piston, a valve casing, valve mechanism in said casing which is oscillated by said rocker plates, an extension housing arranged 60 on said casing, a locking member carried by the valve mechanism and extending into said housing, a semi-spherical rocker seated in the upper end of said extension housing and yielding means co-operating with said 65 locking member and said rocker.

9. A valve mechanism for motors comprising a cylindrical casing, a sleeve mounted within the casing, valve stems arranged in each end of the sleeve and movable longitudinally with respect thereto, a valve spring 70 arranged within the sleeve between the stems and bearing against said stems, and valves carried by the stems and held to their seats by said spring pressure.

10. A valve mechanism for motors comprising a cylindrical valve casing, a cylinder mounted within the casing and carrying loosely mounted valve stems at each end thereof, intake and exhaust valves arranged on said stems and having circumferential 80 lost motion relative thereto, means for rocking said cylinder and operating said valves, means for arresting said valves in their open and closed positions, and means co-operating with said cylinder to hold the same in its 85 extreme positions.

11. A motor comprising a cylinder, a reciprocating piston therein, a valve casing communicating with said cylinder and having intake and exhaust ports, valves in said 90 casing for controlling said ports, means for initially moving said valves, means for operatively interengaging said valves and plural elements cooperating with said valve connection at different points to impart a snap 95 action thereto and complete their movement.

12. A motor comprising a cylinder, a piston, and a valve casing communicating with said cylinder and having intake and exhaust ports, valves in said valve casing, means arranged within said casing for operatively interengaging said valves, means for actuating said interengaging means, said actuating means being arranged wholly within 100 said cylinder and operable by said piston, 105 and spring-pressed members mounted in said casing and cooperating with said interengaging means for imparting snap action to the valves and assisting in the final throw thereof.

13. A motor comprising a cylinder, a piston and valve casing, oscillating valves in said casing, means for initially moving said valves, operating means having a lost motion connection with said valves, and means 115 cooperating with said operating means for imparting a snap action thereto to complete the movement of said valves.

14. In a motor, the combination of a cylinder, its piston, and valve casing, of an oscillating valve in said casing, oscillating mechanism for said valve, means on the piston and located wholly within the cylinder for actuating said oscillating mechanism whereby said valve is partially rotated, and means 125 located wholly within the valve casing for completing the oscillating movement of said valve.

15. In a motor, the combination of a cylinder, its piston and valve casing, of oscillat- 130

ing valves arranged within said casing and provided with means cooperating with said casing for determining the extreme throw of said valves, means for initially moving 5 said valves, operating means having a lost motion connection with said valves, and yielding means cooperating with said operating means for absorbing said lost motion and imparting a snap closing movement to 10 said valves.

16. The combination with a reciprocating piston having a cam projection thereon, a rocking plate operable in one direction by the cam projection on said piston, a valve 15 casing, a valve within the casing, and a connection between said rocking plate and said valve whereby the latter is caused to be moved in one direction.

17. In a motor, the combination of a cylinder and piston, said piston having cam faces on its opposite sides, rocking plates at each end of the cylinder on which said cam faces alternately cooperate to rock said plates, a valve casing, valves mounted in said 25 casing, means for interengaging said valves whereby said valves are caused to oscillate in unison, and connections between said rocker plates and said valves whereby said valves are positively operated by the cam faces on 30 the piston in opposite directions at each stroke of said piston from one end of the cylinder to the other.

18. In a motor, the combination of a valve casing having ported seats, inlet and exhaust 35 valves cooperating with said seats, means on each of said valves respectively for limiting their oscillating movement, an oscillating member, a valve stem carried by said member, one of said valves being loosely mounted 40 on said valve stem and having a lost motion operative connection with said oscillating member and the other valve being loosely mounted on said valve stem and having a lost motion connection therewith, and means 45 for imparting snap movement to said oscillating member.

19. In a motor, the combination of a valve casing having inlet and exhaust valves at its ends, means for limiting the oscillating

movement of said valves, a centrally arranged sleeve, valve stems carried by said sleeve, said inlet valves having lost motion operative connection with said sleeve, and said exhaust valves having lost motion operative connection with said valve stems, and 50 means for oscillating said stems and said sleeve and their controlled valves. 55

20. In a motor, the combination with a valve casing having inlet and exhaust valves at its ends, of means for limiting the oscillating movement of said valves, a centrally arranged sleeve, valve stems carried by said sleeve and having longitudinal movement with respect thereto, certain of said valves having lost motion operative connection with 60 said sleeve, certain other of said valves having lost motion operative connection with said valve stems, a spring arranged within said sleeve and exerting pressure in opposite directions against said valve stems, 65 thereby holding said valves to their seats, arms fixed to said valve stems and adapted to be actuated to oscillate said valve stems and said sleeve, and means for imparting snap action to said sleeve. 75

21. In a motor, the combination with a valve casing having inlet and exhaust ports at its ends, of a centrally arranged sleeve, valve stems carried by said sleeve and having longitudinal movement with respect thereto, 80 means in said sleeve for exerting pressure in opposite directions against said valve stems, inlet and exhaust valves loosely mounted on said valve stems and held in cooperative relation with said inlet and exhaust ports by the pressure exerted against 85 said valve stems, arms fixed to said valve stems and adapted to receive rocking movement whereby said sleeve is oscillated, said inlet valves having lost motion operative engagement with said sleeve and said exhaust valves having lost motion operative engagement with said arms, and means for imparting snap action to said valves. 90

In testimony whereof I hereunto affix my 95 signature this 15th day of April, 1919.

WILLIAM J. MACKLE.
